UNITED STATES PATENT OFFICE.

JOSEPH C. PELLETIER AND DAVID RONDEAU, OF WINNIPEG, MANITOBA, CANADA.

INDEX CUTTER AND PRINTER.

1,302,083.

Specification of Letters Patent. Patented Apr. 29, 1919.

Application filed July 5, 1917. Serial No. 178,793.

To all whom it may concern:

Be it known that we, JOSEPH C. PELLETIER and DAVID RONDEAU, both of the city of Winnipeg, in the Province of Manitoba, 5 Canada, have invented certain new and useful Improvements in Index Cutters and Printers, of which the following is the specification.

The invention relates to improvements in 10 index cutters and printers and the object of the invention is to provide a machine whereby pages or sheets can be cut and indexed in the one operation and further such that the complete work of indexing, say for the 15 entire alphabet, can be done.

With the above principal objects in view and other minor objects which will appear as the description proceeds, the invention consists essentially in the arrangement and 20 construction of parts hereinafter more particularly described and later pointed out in the appended claims, reference being had to the accompanying drawings in which:—

Figure 1 represents an end view of the 25 complete machine.

Fig. 2 represents a front view thereof.

Fig. 3 represents an enlarged detailed front view of the printing and cutting parts.

Fig. 4 represents an end view of the lat- 30 ter parts.

Fig. 5 represents an enlarged detailed vertical sectional view through the ink box.

Fig. 6 represents an enlarged detailed vertical sectional view through the release pin.

Fig. 7 represents a perspective view of the 35 release pin collar.

In the drawings like characters of reference indicate corresponding parts in the several figures.

1 and 2 represent a pair of end standards 40 mounted on the base piece 3 and connected by a cross top beam 4 which is securely bolted to the standards.

5 and 6 represent opposing vertically dis- 45 posed guides secured permanently to the upper ends of the standards and receiving sliding blocks 7 and 8 secured to and extending from the ends of the top knife beam 9. Vertically disposed lining rods 10 and 11 are in-

50 terposed between the top beam 4 and the base 3 and pass through the beam 9 and the blocks, these rods preventing one end of the knife beam from getting ahead of the other when pulled down. The knife beam is sus- 55 pended in horizontal position by coiled

springs 12 and 13 attached to the top beam and to the knife beam.

In the operation of this machine it is necessary to pull the knife beam down against the up-pull of the springs and we have accomplished this in the present disclosure by means of a foot pedal 14 carried by end pivot bars 15 and 16 and connected by up-standing rods 18 and 19 to outstanding bars 20 and 21 secured permanently to the knife beam.

The upper ends of the rods 18 and 19 are threaded where they enter the bars and are supplied with upper and lower nuts 22 and 23 whereby the rods can be adjusted in respect to the bars.

Obviously the knife beam will be forced down if one press the foot pedal down with his foot.

Toward the back of the machine we locate 75 a horizontal screw shaft 24 which passes lengthwise of the machine and has the end thereof suitably mounted in the end standards the mounting being such that the shaft can be rotated a fixed amount by turning the end indicator 25 by the hand.

It is here to be noticed that the shaft has no end movement, only a rotary one around its central axis.

In advance of the shaft we place a guide 80 beam 26 which is parallel with the shaft and has the ends thereof permanently secured to the end standards. On the shaft and on this beam we mount a shiftable knife carriage 27 which embodies a front bar 28 slidably mounted on the beam 26 and two back-turned end extensions 29 and 30 which are threaded to receive the shaft.

Obviously from this arrangement the turning of the shaft will effect the traveling 95 of the knife carriage to the left or right as desired and a fixed amount determined by the pitch of the threads and the amount that the indicator is turned.

Directly above the lower carriage 27 we 100 locate an upper knife carriage 31 which is slidably suspended from the beam 9 by hook shaped hangers 32. This top carriage is caused to move with the bottom carriage and for this purpose we provide extending 105 carrier bars 33 and 34 secured permanently to the top carriage and connected slidably to the bottom carriage, the arrangement being such that in the movement of the bottom carriage under the control of the shaft the top 110

carriage will be compelled to slide correspondingly on the beam 9 and such that in the downward movement of the beam 9 the carrier bars will slide in respect to the lower carriage to accommodate the movement. The lower carriage carries the lower knife 35 which is of an elongated L-shape with the turned end directed toward the shaft.

The upper edge of the knife is sharpened and is contained in the horizontal plane. Directly above the lower knife and mounted on the top carriage is the top knife 36 which is also of an elongated L-shape and has the lower or cutting edges thereof inclining gradually downwardly as indicated at 37 and 38 to the corner where they meet in a downwardly projecting point 39. This upper knife is positioned so that when cutting it will pass to the inside of the lower knife.

20 The machine as hereinbefore disclosed will do the index cutting as it will be obvious that upon a sheet or several sheets being placed between the knives and the foot pedal, being pressed down, the knives will

25 cut a strip out of the paper and leave an indexing tab as is customarily found on indexed pages. After the first tab has been cut the indicator is turned the proper amount and a further sheet is inserted and 30 the foot pedal again pressed. This cuts the sheets to provide for the second indexing tab which would be longer than the first, depending on the adjustment given the knives in respect to the sheet or sheets which in all 35 cases, it will be understood, are fed in at the same point, the knives alone being shifted.

By continuing this operation a whole series of indexing tabs can be cut accurately and quickly.

40 The printing is accomplished by the following parts:—

The lower knife carrier carries an indexing printing strip 40 and an ink box 41, while the upper carriage carries a printing roller 42, a platen 42', and a roller shifting appliance 42*. The printing strip 40 is provided with raised characters such as say the letters of the alphabet and it is mounted on a lower circular roller 43 and an upper flat 45 sided roller 44, the rollers being carried by short spindles 45 and 46 located at the ends of adjustably connected vertically disposed bars 47 and 48. The upper spindle 46 projects from the upper carriage and the top 50 roller turns on the top spindle.

Between the top roller and the ink box we have the roller 42 which is suitably carried by a bracket 42* secured to the top carriage and at the lower end of the ink box we supply a feed roller 49 which in the manipulation of the machine is adapted to deposit ink from the box on to the printing roller 42 which in turn inks the raised characters of the strip.

65 The platen 42' is placed directly above the

top roller, being arranged such that when it is brought down by the manipulation of the beam 9 it will press against the face of the then top character of the strip. Obviously if paper be placed between the strip and the platen the impression of the character will be made on the paper when the beam 9 goes down.

In utilizing this device to print the letters of the alphabet it is necessary to rotate the strip one letter displacement each time the beam is depressed and this is accomplished by a spring catch 50 secured to the top carriage and engaging with a ratchet wheel 51 located at the end of the top roller. Any suitable appliance such as a flat friction spring 52 secured to the side bar 47 can be used to prevent the roller being turned by the catch when it passes down. In the upward movement of the beam the catch is designed to engage the ratchet wheel and turn the roller so that a new and the following letter is presented on the top side.

The top roller is positioned in respect to the knives so that at the time any particular indexing tab is cut a letter will be impressed on the tab of that sheet. Accordingly, if one set the strip so that say the first letter of the alphabet is up when the first tab is cut, then he can operate the machine continuously and cut and print all the necessary tabs for the complete alphabetical index.

While we have described the various parts of this machine in detail, we wish it to be understood that we do not wish to be limited to the precise arrangement shown as other constructions serving the same functions could be readily substituted without in the least departing from the spirit of the invention and while coming under the scope of the appended claims.

The upper knife 36 is hinged as indicated at 36* to allow the said knife to be swung out so that two or more letters can be printed on the one tab if desired without the knife cutting. Any convenient means such as a catch 36* can be used to hold the knife in the normal or cutting position.

It is desirable, where long shifts on the knife carriages are required, to provide a means for permitting this to be done without having to turn the indicator. We accomplish this in the present case by mounting a spring pressed pin 53 on each of the back turned extensions 29 and 30, the inner ends of the pins normally riding between the threads of the shaft. The upper end of each pin is formed into a head 54 which is fitted with a finger ring 55 and the lower side thereof flattened to enter opposing slots 56 and 57 formed in a sleeve 58 seated on the extension in each case.

Obviously from this arrangement when the pins are in the carriages will be caused to move backwardly and forwardly when

the indicator is turned. However, if one wishes to move the carriages without turning the indicator he simply pulls up the finger ring to release the pin and then turns 5 the finger ring a quarter turn so that the flat sides thereof will ride the top ends of the sleeve in which positions the pins are clear of the threads. The carriages can then be shifted freely by direct hand application 10 and manipulation.

What we claim as our invention is:—

1. In an index cutting and printing machine, the combination with a lower knife carriage, a substantially L-shaped knife 15 blade mounted on the carriage, an upper suitably mounted knife carriage, a substantially L-shaped upper knife carried by the upper carriage and means for manipulating the upper knife carriage to bring the knives 20 into cutting relation, of an endless indexing printing strip carried by the lower knife carriage and located at one end thereof and presenting a series of printing characters, means for inking the strip, a platen

carried by the upper knife carriage and 25 means for automatically bringing the indexing characters successively to a position under the platen to effect the printing of a character each time the knives are brought into cutting relation. 30

2. In an index cutting and printing machine in combination, a lower stationary substantially L-shaped cutting knife having the cutting edges contained in the horizontal plane and an upper vertically movable 35 coacting substantially L-shaped cutting knife having the cutting edges thereof contained in oppositely inclining planes terminating at their intersection in a downwardly extending piercing point. 40

Signed at Winnepeg, this 12th day of April, 1917.

JOSEPH C. PELLETIER.
DAVID RONDEAU.
